UNITED STATES PATENT OFFICE

128,896

DESIGN FOR A DRESS

Bonnie Cashin, New York, N. Y.

Application July 19, 1941, Serial No. 102,267

Term of patent 3½ years

To all whom it may concern:

Be it known that I, Bonnie Cashin, a citizen of the United States, residing in New York city, in the county of New York and State of New York, have invented a new, original, and ornamental Design for a Dress, of which the following is a specification, reference being had to the accompanying drawing, forming part thereof.

Fig. 1 is a front view of a dress showing my new design.

Fig. 2 is a rear view of Fig. 1, and Fig. 3 is an enlarged fragmentary side view thereof.

I claim:

The ornamental design for a dress, substantially as shown.

BONNIE CASHIN.
